[57] CLAIM

The ornamental design for a wristwatch case and band, as
shown and described.

DESCRIPTION

FIG. 1 is a top plan view of a wristwatch case and band
showing my new design;

FIG. 2 is a bottom plan view thereof;

FIG. 3 is a right side elevational view thereof; and,

FIG. 4 is a left side elevational view thereof.

The broken line showing of FIG. 1 is environmental only
and forms no part of the claimed design.
